The ornamental design for a device for carrying shopping bags, as shown and described.

DESCRIPTION

FIG. 1 is a front elevational view of a device for carrying shopping bags, showing my new design, the rear elevational view being a mirror image thereof;

FIG. 2 is a top plan view thereof;

FIG. 3 is a bottom plan view thereof;

FIG. 4 is a right side elevational view thereof; and,

FIG. 5 is a left side elevational view thereof.

FIG. 1

FIG. 4 FIG. 5

FIG. 2

FIG. 3
